UNITED STATES PATENT OFFICE.

LEWIS L. ROGERS AND ALBERT C. ROBBINS, OF ORANGE, MASSACHUSETTS; SAID ROBBINS ASSIGNEE TO SAID ROGERS.

SHEET-GAGE FOR PRINTING-PRESSES.

1,095,125.

Specification of Letters Patent. Patented Apr. 28, 1914.

Application filed August 1, 1912. Serial No. 712,620.

To all whom it may concern:

Be it known that we, LEWIS L. ROGERS and ALBERT C. ROBBINS, citizens of the United States, and residents of Orange, in 5 the county of Franklin and State of Massachusetts, have invented certain new and useful Improvements in Sheet-Gages for Printing-Presses, of which the following is a specification.

- 10 This invention relates to a sheet-gage for a printing press, and particularly to a side-gage for a one-cylinder, two-revolution press in which the cylinder is movable up and down relatively to a horizontally re- 15 ciprocating form and bed; and the principal object of the invention is to provide a gage, and especially a side-gage, which is automatically movable to its working position for locating an edge of a sheet to be 20 printed, this movement being preferably controlled by an element of the press itself, and, in the case of a one-cylinder, two-revolution press, usually by the rise of the cylinder of the press.
- 25 A further important feature of the invention is an automatically movable gage which is automatically shiftable away from the surface of a sheet and its support—usually the feed-table—for the purpose of 30 releasing the sheet when the gaged edge thereof is in readiness for engagement by the usual gripping means of the press. In connection with this movement of the gage one feature of the invention relates to means 35 for actuating the gage in proper timing with the gripping means of the press.

Other features of the invention not hereinbefore referred to will be hereinafter described and claimed and are illustrated in 40 the accompanying drawings, in which—

Figure 1 is a plan of a portion of one type of printing press—to wit, a one-cylinder, two-revolution press—embodying gages constructed in accordance with this 45 invention; Fig. 2 is a sectional elevation of the front side of the same; Fig. 3 is an enlarged detail illustrating in elevation and longitudinal section the construction of one of said side-gages, its operating means and 50 certain parts with which it coacts, showing the cylinder up and the gage forward and beginning to rise to clear a sheet; Fig. 4 is a similar view showing the cylinder farther down and the gage in position and back, 55 and Fig. 5 is an enlarged plan of the gage

and its actuating means in operative relation with the feed-table.

Similar characters designate like parts in all the figures of the drawings.

As before stated, the principal feature of 60 the invention is a gage automatically shiftable to its working or sheet-gaging position. So long as suitable means is provided for effecting this automatic movement of the gage the gage itself may be of any well-known or suitable type and construction. 65 The gage shown is similar in many respects to sheet-gages, and especially side-gages, heretofore used in printing presses, though specifically it differs considerably from 70 gages heretofore used for a similar purpose.

The gage as a whole is designated generally by S and comprises a main frame or base-plate, a gage proper, a spring tongue or guard for engaging the adjacent edge of 75 a sheet delivered on to the feed-table of the press, and suitable means for supporting the gage and the tongue or guard on the base-plate and adjusting them for proper co-operation with the feed-table and with 80 sheets delivered on to it. A suitable base-plate is illustrated at 2, it being supported on the main fixed frame of the press in such a manner as to permit the movement of the gage proper toward and from its working 85 position. It is also supported on said frame-work in such a manner as to permit another movement of the gage, which movement will be hereinafter described.

The gage proper may be substantially of 90 the usual type employed in printing presses for gaging the edges of sheets fed by hand to the machine, it being indicated here in at 3. Co-operating therewith is also the usual spring tongue or guard, 4, for assuring 95 the proper delivery of a sheet with its edge flat. Both the gage proper and this tongue or guard are in this case carried by and removably secured to a gage-rod, 5, adjustable back and forth with respect to the main 100 frame or base-plate 2 of the gage, said rod being supported directly in a tubular member, 6, to slide therein as adjusted, and the tubular member being mounted in bearings 105 in uprights, 7 and 8, rising from the base-plate 2. The tubular member 6 and the parts just described carried by it are intended to slide in said bearings according as the gage is moved toward or from its 110 working or gaging position. Suitable means

are employed for limiting the return movement of the gage-rod and the gage, a stop being provided for determining the position of these parts on said return stroke. This stop is shown as formed on a cross-head, 10, mounted on the forward end of the tubular member 6 in position to engage the forward end of the riser 8 and be stopped thereby on the return stroke of the gage, as shown in Fig. 4. This cross-head 10 is also shown as having a depending lug, 11, with an opening in it to permit it to slide back and forth on a guide 12, projecting from the forward end of the base-plate 2, this construction serving to hold the cross-head positively against turning movement on the tubular member 6 while at the same time allowing it to slide freely thereon.

The gage-rod 5 should also have a suitable adjustment for controlling the positions of the gage proper 3 and the tongue or guard 4 with respect to the edge of a sheet. In the present case this adjustment is controlled by a threaded rod, 13, in fixed relation with the rod 5 and extending through an opening, 14, in the upper part of the cross-head, and also by a pair of knurled adjusting and check nuts, 15 and 16, mounted on the threaded rod 13 and co-operative therewith and with the adjacent cheeks of the upper part of the cross-head 10 in a manner which will be clear. By suitably adjusting the nuts 15 and 16 the gage-rod, the gage and the guard may be shifted to any desired adjusted position and held there in the desired fixed relation to the tubular member 6.

Normally the parts just described, to wit, the gage, the guard, etc., will preferably be held in the relation to the base-plate 2 that is illustrated in Fig. 4, a spring, such as 17, being illustrated as working between the riser 8 of the base-plate and a suitable stop, such as 18, on the tubular member 6 for the purpose of normally retracting the gage, etc., to this position. When the gage is to be shifted forward to its working or gaging position this will be effected by suitable automatic means, the power exerted by which is superior to that of the spring 17.

The movement of the gage and other parts co-operative therewith to a forward or working position may be automatically brought about at the proper time by any suitable means carried by a printing press. When the gage is used on a hand-fed printing press of the one-cylinder, two-revolution type specifically illustrated in the drawings, in which a cylinder such as C, reciprocates up and down to permit the passage of a form, f, and a reciprocating bed, b, under it, this forward movement of the gage to its working position will preferably be controlled by the rise of said cylinder. In the construction specifically illustrated this working

movement of the gage is intended to be effected from a vertically movable horizontal press-rod, 19, carried by the movable frame, M, which supports the cylinder C and works up and down in the fixed frame, F, of the press in a manner well understood. This press-rod 19 of course rises with the cylinder, being in fixed relation with the axis of the cylinder, and constitutes, in this case, the main element of the automatic means for moving the gage forward at the proper time. This automatic means also embodies in the construction illustrated a cam and a cam-actuator one of which is carried by the gage and the other mounted to move up and down with said cylinder and press-rod. Here the cam-actuator is secured to the press-rod and the cam is attached to the gage, said press-rod having thereon a plurality of collars, 20, one for each of the side-gages employed and each carrying preferably an antifriction roller or cam-roller, 21, journaled in lugs, 22, projecting from the collars 20 and in position to co-operate with suitable cams carried by the gages. Each of these collars is also preferably shiftable or adjustable to any desired position lengthwise of the press-rod 19 and when in the position desired is held there, as by a set-screw, 23. The cam carried by the gage may be of any proper type for effecting the desired movement of the gage and other parts, but in order that it may co-operate with its actuator, the cam-roller 21, under all conditions, and particularly when the gage is shifted transversely to and away from the sheet gaged by it, as will presently be described, it is preferable to make it as shown in the drawings, that is, with a working face substantially concentric with the axis of a fixed press-rod, 24, on which the gage is directly mounted. Here this cam is shown as embodied in a bent rod, 25, one end of which is inserted in the rear end of the tubular member 6 of the gage and is securely held in place therein, as by means of a set-screw, 26, passing through a boss forming the stop 9. It will be seen that the cam 25 is also adjustable, its forward end being shiftable to different positions in the tubular member 6 in any of which it may be clamped and held by said set-screw 26. In any of the positions to which it may be set this cam is substantially concentric with the axis of the press-rod 24 and in any of these positions it will co-operate properly with the roller 21 and will permit the lifting of the gage from the sheet. The manner in which this lifting movement is preferably accomplished will now be described.

The gage and all its parts will usually have, in addition to the reciprocating, substantially horizontal movement before described, a movement transverse to a sheet gaged by it, this movement being, in the con-

struction illustrated, an oscillatory one about the axis of the press-rod 24. This rod is mounted in suitable bearings at opposite sides of the press for rocking movement and to it are secured a number of gages corresponding in number and position to the collars and rollers 20 and 21. As shown, the base-plate of each gage forms a bracket extension of a collar, such as 27, which is secured to the rod 24 in any desired angular position, as by means of a thumb-screw, 28. When fastened in place on the rod 24 each gage constitutes a rock-arm that rocks with the rod or shaft 24. The rocking movement of this rod 24 may be controlled automatically by any suitable means on the press. In this case the oscillation of the side-gages 3 is intended to be effected in proper relation with the operation of the gripping means, the means employed for imparting movement to the devices for actuating the grippers being also illustrated as used to impart movement to the devices for rocking the shaft 24. At one end thereof this shaft 25 is shown as having a rock-arm, 29, which is intended to be raised by an arm, 30, pivoted on the press-rod 19 and movable up and down therewith, and coöperating at its forward end with a cam, 31, in fixed relation 30 with a gear-wheel, 32, driven by a pinion, 33, secured to the shaft of the cylinder C. Through these connections the cam 31 rotates in proper timing to the revolutions of the cylinder C. The dotted line positions of 35 the parts, shown in Figs. 2 and 3 and also in Fig. 4, show the rock-arm 29 and the swinging arm 30 in the positions they occupy when the gage is down and in position to coöperate with the side of a sheet. The dot and dash lines in Fig. 3 show the positions occupied by these parts when the rock-arm 40 29 is raised to oscillate the gage away from the surface of a sheet to permit the engagement of such sheet by the grippers. 45 As is usual, the gear-wheel 32 also has in fixed relation therewith a cam, such as 34, controlling the throw of the grippers. The grippers themselves may be of the usual type, as indicated at 35, and mounted on a 50 rock-shaft, 36, revolving with the cylinder C. At one end thereof this rock-shaft carries a cam-segment, 37, coöoperative with an actuating pin, 38, mounted at the upper end of the main frame and having at the 55 under side of its outer end a groove in which works the edge of a cam-wheel 34. This pin is reciprocated by said cam-wheel at the proper times in the usual manner to cause the grippers 35 to engage the forward side 60 of a sheet, s, on the feed-table, so that the sheet may be carried around by the cylinder to the point of impression and properly printed after the form has been inked by the inking means, such as the ink-roller i. 65 The same cam 34 which controls the pin 38

may also serve to operate, through a suitable connection such as a lever, 39, an automatically movable element, 40, of an end gage, E, having a gage face, 41, not automatically movable, for effecting a preliminary gaging 70 of the end of a sheet, gages, such as 42, carried by the automatically movable element 40 serving to push the sheet into proper position in one direction. The side gages 3 serve in a similar manner to push the side 75 of the sheet into proper position in the other direction. Both of these actions of the gages will, of course, take place prior to the engagement of the gaged sheet by the grippers 80 35. The specific features of the end-gage E and the means for operating the same constitute no part of this invention but form the subject matter of a companion application, Serial No. 712,621, filed August 1, 1912, and are described in detail therein. 85

In operation, a sheet, s, is fed, usually by hand, on to the feed-table and is engaged by the end stop 41 and is also brought at its forward side into position to be engaged by the side-gages 3. It being understood that 90 the cylinder C is rising after having finished its printing revolution the rollers 21 come into contact with the cams 25 at the proper point in the rise of the cylinder, and move the side-gages 3 forward to push the sheet s 95 - automatically into place on the feed-table and gage the side of the sheet. At substantially the same time, and in advance of the operation of the grippers, the end-gage faces 42 of the end-gage E are shifted automatically forward to push the rear end of the sheet into place and gage it. Thereupon the cam 34 operates in the usual manner to actuate the grippers 35 to engage the forward end of the sheet on the feed-table and at substantially the same time the cam 31, operating through the swinging arm 30 and the rock-arm 29, oscillates the side-gages and they begin to rise to clear the gaged sheet. 105 On the descent of the cylinder to effect 110 another impression the side-gages 3 are drawn back by their springs 17 to the position shown in Fig. 4 and remain in that position until another sheet is in position to be gaged. At the same time the side-gages descend owing to the withdrawal of the cam 31 from the end of the swinging arm 30. 115

What we claim is:

1. In a sheet-gage for a printing press in which the cylinder is bodily reciprocable, the 120 combination with a gage proper associated with the feed-table of said press, of means movable with said cylinder for shifting said gage to a working position with respect to said feed-table.
2. In a side gage for a printing press in which the cylinder is bodily reciprocable, the combination with a gage proper associated with the feed-table of said press, of means movable with said cylinder for shifting said 130

gage in the line of travel of a sheet into the press to a working position with respect to said feed-table.

3. In a sheet-gage for a printing press in which the cylinder is bodily reciprocable, the combination with a sliding gage associated with the feed-table of said press, of means movable with said cylinder for sliding said gage to a working position with respect to said feed-table, and means for automatically returning said gage to its initial position.

4. In a sheet-gage for a printing press in which the cylinder is bodily reciprocable, the combination with a gage proper associated with the feed-table of said press, of a spring for holding said gage in a normal retracted position, and means movable with said cylinder for advancing said gage to a working position with respect to said feed-table.

20 5. In a sheet-gage for a one-cylinder two-revolution printing press in which the cylinder is bodily reciprocable, the combination with a gage proper associated with the feed-table of said press, of automatic means whereby the rise of said cylinder shifts said gage to a working position with respect to said feed-table.

6. In a sheet-gage for a one-cylinder two-revolution printing press, the combination with a gage proper associated with the feed-table of said press, of automatic means governed by the rise of said cylinder for shifting said gage to a working position with respect to said feed-table, said means embodying a cam and a cam-actuator one of which is secured to the gage and the other mounted to move up and down with said cylinder.

7. In a one-cylinder two-revolution printing press in which the cylinder is bodily reciprocable, the combination with a plurality of side gages associated with the feed-table of said press, of automatic means movable up and down with said cylinder for shifting said gages simultaneously to their working positions with respect to said feed-table.

8. In a one-cylinder two-revolution printing press, the combination with a horizontal rod carried by the main frame, of a plurality of side gages secured to said rod and associated with the feed-table of said press, a horizontal rod mounted to move up and

down with said cylinder, and a plurality of actuators secured to said last-named rod for automatically shifting said gages simultaneously to their working positions with respect to said feed-table.

9. In a sheet-gage for a printing press, the combination with a gage proper associated with the feed-table of said press and movable into and out of working position substantially in the plane of said feed-table and also movable up and down transversely to the plane of said feed-table, of automatic means governed by a movable element of said press for shifting said gage in said first path to a working position, sheet-gripping means, and automatic means for raising said gage in said second path on the gripping of a gaged sheet.

10. In a sheet-gage for a printing press, the combination with a gage proper associated with the feed-table of said press and mounted to slide into and out of working position substantially in the plane of said feed-table and to oscillate transversely to said plane, of automatic means governed by a movable element of said press for shifting said gage in said first path to a working position, sheet-gripping means, and automatic means for oscillating said gage to release a gaged sheet after its engagement by the gripping means.

11. In a one-cylinder two-revolution printing press, the combination with a gage proper associated with the feed-table of said press and mounted to slide into and out of working position substantially in the plane of said feed-table and to oscillate transversely to said plane, of automatic means governed by the rise of said cylinder for shifting said gage in said first path to a working position, sheet-gripping means, and automatic means governed by the revolution of said cylinder for swinging said gage upward on the gripping of a sheet.

Signed at Orange, in the county of Franklin and State of Massachusetts, this 30th day of July, A. D. 1912.
